ELECTRIC POWER HANDLE FOR A MANICURING IMPLEMENT OR SIMILAR ARTICLE

Theodore G. Daher, Stratford, Conn., assignor to General Electric Company, a corporation of New York

Filed May 12, 1966, Ser. No. 2,272

Term of patent 14 years

(Cl. D86—10)

FIG. 1

FIG. 2

FIG. 3

FIG. 4

FIG. 5

FIG. 6

FIG. 1 is a side perspective view of an electric power handle for a manicuring implement embodying my new design;

FIG. 2 is a front elevational view thereof;

FIG. 3 is a rear elevational view thereof;

FIG. 4 is a top plan view thereof;

FIG. 5 is a side elevational view thereof; and

FIG. 6 is a bottom plan view thereof.

I claim:

The ornamental design for an electric power handle for a manicuring implement or similar article, substantially as shown.
